SLEEVE STRETCHER OR THE LIKE

Manuel Lopez, Akron, Ohio

Application August 25, 1947, Serial No. 770,473

3 Claims. (Cl. 223—74)

1

This invention relates to mechanism for stretching or forming dress and coat sleeves, and the like, and, more particularly, is concerned with stretching apparatus which can be inserted inside of a sleeve and expanded to properly hold or shape a sleeve during a cleaning, dressmaking, or other similar operation.

Heretofore, sleeve stretchers have been provided, but the known stretchers are open to various objections. For example, one type of sleeve stretcher is too complicated and expensive. Other known sleeve stretchers do not do a good stretching job the full length of a sleeve. Other sleeve stretchers are not readily expanded or collapsed to facilitate entry or removal of the stretcher with respect to a sleeve.

It is the general object of my invention to avoid and overcome the foregoing and other difficulties of and objections to known sleeve stretchers by the provision of an improved, relatively inexpensive, light weight, easily operated, and long lived stretcher for sleeves and the like.

Another object of my invention is to provide a sleeve stretcher, or the like, which can be readily collapsed or expanded, and when in expanded position is quickly and resiliently locked to apply a continuing tension on a sleeve.

Another object of my invention is the provision of an inexpensive, substantially fool-proof, and readily handled locking mechanism for holding a sleeve stretcher in expanded position.

The foregoing objects of my invention, and other objects which will become apparent as the description proceeds, are achieved by a mechanism including a bar, a bell crank pivotally secured to the bar adjacent one end, a second bar pivotally secured near its center to one end of the bell crank and movable toward and from the first bar upon movement of the bell crank, a locking means on the end of the first bar, and a flexible cord extending from the other end of the bell crank through the locking means. The bell crank is usually resilient so as to apply a tension upon a sleeve or the like being stretched, and the locking means usually include a pivotally mounted jaw engaging in wedging relation with the cord.

For a better understanding of my invention, reference should be had to the accompanying drawings, wherein:

Fig. 1 is an elevational view of the side of a sleeve stretcher incorporating the principles of my invention;

Fig. 2 is an elevational view of the edge of the stretcher illustrated in Fig. 1;

Fig. 3 is a transverse vertical cross-sectional

2

view, on an enlarged scale, and taken substantially on line III—III of Fig. 1;

Fig. 4 is a longitudinal cross-sectional view in fragmentary form, and on the scale of Fig. 3, taken substantially on line IV—IV of Fig. 2;

Fig. 5 is a view similar to Fig. 4, but taken substantially on line V—V of Fig. 2; and

Fig. 6 is a longitudinal vertical cross-sectional view, on the scale of Fig. 3, taken on substantially line VI—VI of Fig. 2 and illustrating details of the locking mechanism.

In the drawings, the numeral 10 indicates a bar of elongated form, and usually curving in its length to better conform to the shape of a sleeve to be stretched, the sleeve being indicated in chain dotted lines by the numeral 12. Associated with the bar 10 is a second bar 14 of similar shape to the first bar 10, but with the bar 14 being usually made somewhat shorter in length than the bar 10.

The bars 10 and 14 are mounted for movement toward and from each other in substantially parallel relationship, and this is achieved in the form of my invention illustrated by providing a resilient bell crank 16 having a relatively short arm 18 and a longer arm 20. The end of the longer arm 20 of the bell crank is pivotally secured, as at 22, to substantially the center of the bar 14, and this is usually achieved in the manner best illustrated in Fig. 4, by forming the bar 14 with a longitudinally extending groove 24. The end of the arm 20 extending down into the groove 24 is formed with an eye portion 26 which surrounds a roller 28 carried on a pin or rivet 30 which extends completely through the bar 14 to provide the pivot 22.

The bend of the bell crank 16 is formed with a loop portion 32 which extends down into an arcuate groove 34 formed in the bar 10 a short distance from one end thereof. The loop portion 32 of the bell crank surrounds a roller 36 carried upon a pin or rivet 38 to provide a pivotal support 41 for the bell crank on the bar 10, the rivet or pin 38 extending from side to side through the bar 10 in the manner illustrated.

The short arm 18 of the bell crank 16 has a cord 40 or other flexible element secured thereto, and this is conveniently accomplished by means of a clip 42 which is removably fastened to the end of the arm 18, the clip 42 having a wedge shaped ferrule and clamping teeth for releasably gripping the end of the cord 40. It will be understood that the cord 40 will be released from the clip 42 only when it is necessary to replace a worn cord

with a new one after the continuous use of the stretching apparatus over long periods of time.

The end of the bar 10 adjacent the short arm 18 of the bell crank 16 is formed with a recess 44 therein, a hole 46 connecting the recess 44 with the edge of the bar 10, and with the cord 40 extending through the hole 46 and recess 44 in the manner illustrated in Fig. 6 of the drawing. Received within the recess 44 is a jaw 48 which is pivotally mounted on a pin 50 extending through the bar, the jaw 48 being adapted to be moved from the non-locking position shown in full lines into locking relation with the cord 40 as indicated in the dotted lines in Fig. 6. When in locking relation with the cord 40, it will be evident that a downward pull on the cord 40 causes the jaw 48 to wedge the cord 40 tightly against the wall of the recess. The jaw 48 usually has small teeth formed on a lip portion 52 which assist in the locking action. Also, it is to be noted that the jaw 48 has the lip portion 52 extending substantially out of the recess 44 when the jaw is in non-locking position, and when in this position, the cord can be tilted to engage with the lip portion of the jaw so as to effect the locking action of the jaw when pull is exerted on the cord in the opposite or downward direction in Fig. 6.

A cover plate 54 is secured over the top of the recess 44, the cover plate having a suitable opening, usually substantially square, to permit the movement of the cord and the lip portion of the jaw therethrough.

In the operation of the improved stretching mechanism just described, the bars 10 and 14 are first moved from the full line position shown in Fig. 1 of the drawing to the collapsed position shown in chain dotted lines in Fig. 1. Thereupon, the end of the bars most distant from the bell crank 16 are inserted either into the cuff or shoulder end of the sleeve. Actually, it does not make very much difference which, although in the form of the invention illustrated in Fig. 1 the stretching mechanism has been inserted into the sleeve from the cuff end thereof. Thereupon, the bars 10 and 14 are moved apart and this is achieved by pulling on the cord 40 by way of the knob 56. For example, movement of the knob 56 from the dotted to the full line position shown in Fig. 1 will cause the bars 10 and 14 to move from the dotted to the full line position to expand the sleeve. The pivotal connection 22 between the arm 20 and the bar 14 allows the bar 14 to adjust itself to the width of the sleeve so that pressure will be applied by the bar to the sleeve over substantially the full length of the sleeve. It sometimes helps in applying the expanding force to the mechanism to have the operator grip the short arm 18 of the bell crank to squeeze it towards the bar 10. The bell crank is made of good quality spring steel, usually in the form of a round steel rod, so that any amount to which the bell crank is stressed will be imparted continuously to the sleeve in the stretching operation.

With the bars 10 and 14 in expanded position in the manner just described, the cord 40 is locked by the jaw 48 to hold the sleeve in a stretched, flat position so that cleaning operations, pressing operations, and the like, on the sleeve are facilitated, all without shrinkage on the sleeve. To release the locking mechanism all that is necessary is to pull on the knob 56 to release the lip 52 of the jaw 48 from the cord, and with the jaw 48 tipped or held out of the way the cord

will slide back to allow the bars 10 and 14 to be moved to the collapsed position.

The bars 10 and 14 are preferably made from a light weight, clean, and strong wood, but it may be possible to make the bars from metal or plastic.

From the foregoing, it will be recognized that the various objects of my invention have been achieved by the provision of a readily operated, light weight, long wearing sleeve stretching device which facilitates cleaning, pressing and similar operations upon sleeves of dresses, coats, and other garments. If the bars 10 and 14 are made substantially straight and with sharper edges, it will be seen that the mechanism of my invention can be used to stretch pant legs.

While in accord with the patent statutes, one best known embodiment of my invention has been illustrated and described in detail, it is to be particularly understood that I am not to be limited thereto or thereby, but that the scope of my invention is defined in the appended claims.

I claim:

1. Apparatus for stretching and forming garment sleeves including a pair of relatively thin bars of slightly different length, the bars being curved longitudinally to substantially conform to the contour of a sleeve, a spring wire rod, means pivotally securing the rod at one end to approximately the center of the shorter bar, said means including an eye on the end of the rod, a roller inside the eye, and a pin secured to the bar and rotatably supporting the roller, the rod being bent to have an angularly offset end at the end remote from its pivotal connection to the shorter bar, means pivotally connecting the rod in the region of its bend to the longer bar a short distance from the end of the longer bar, said means including an eye on the rod, a roller inside the eye, and a pin secured to the bar and rotatably supporting the roller, a flexible element connected to the end of the angularly offset end of the rod, a releasable locking mechanism on the end of the longer bar and through which the flexible element extends, and a knob on the end of the flexible element, said locking mechanism including a pivotally mounted jaw adapted to have wedging locking action on the flexible element.

2. A sleeve stretcher or the like including a pair of elongate members, means mounting the members for movement towards and from each other in substantially parallel relation, means pivotally mounting at least one member near its center so that the members will adjust themselves to engage opposite portions along the inside of a sleeve or the like, and means resiliently locking the members in expanded position, said means including a resilient bell crank, a cord secured to an end of the bell crank, one of the members having a hole therein through which the cord extends, a jaw pivotally mounted inside the hole and upon attempted movement of the cord in one direction, adapted to wedge the cord against the wall of the hole, the unpivoted end of the jaw extending out of the hole when in non-locking position so that the cord can be engaged with it to effect the locking of the jaw on the cord.

3. Apparatus for stretching and forming garment sleeves including a pair of relatively thin bars of slightly different length, the bars being curved longitudinally to substantially conform to the contour of a sleeve, a spring wire rod, means pivotally securing the rod at one end to approximately the center of the shorter bar, said means

including an eye on the end of the rod, a roller inside the eye, and a pin secured to the bar and rotatably supporting the roller, the rod being bent to have an angularly offset end at the end remote from its pivotal connection to the shorter bar, means pivotally connecting the rod in the region of its bend to the longer bar a short distance from the end of the longer bar, said means including an eye on the rod, a roller inside the eye, and a pin secured to the bar and rotatably supporting the roller, a flexible element connected to the end of the angularly offset end of the rod, and a locking mechanism on the end of the

longer bar adapted to releasably engage with the flexible element.
